FOLDING STORE SERVICE TRUCK

Sylvan N. Goldman, Oklahoma City, Okla.

Application April 17, 1940, Serial No. 330,184

6 Claims. (Cl. 280—36)

This invention relates to a store service truck, particularly useful in chain stores where the customers must travel from one counter to another for various purchases, and it consists in the constructions, arrangements and combinations herein described and claimed.

It is a particular object of the invention to provide a carrier of a collapsible or folding type, which may be readily collapsed for storage purposes, or readily set up for use.

It is a further object of the invention to provide a folding carrier which, when in folded position, will occupy but little space, and in which the supporting or the traction wheels are completely removed from the floor, thereby avoiding possibility of movement of the carrier from its stored position.

It is a still further object of the invention to provide a pair of spaced superposed basket supporting frames, the upper one of which may be swung to a position out of the way for placement of the usual carrier basket on the lower basket platform and in which the uppermost basket frame cooperates with the supporting structure of the front carrier in a manner to effect collapse of the entire carrier to its folded position.

It is a still further object of the invention to provide a folding carrier which may be readily moved into either position with a minimum of effort, and in which movement to an erected position of the basket frame elements and wheel mountings is automatic due to action of gravity.

Additional objects, advantages and features of invention will be apparent from the following description considered in conjunction with the accompanying drawings, wherein

Figure 1 is a perspective view of my carrier in erected or operative position.

Figure 2 is a front view thereof.

Figure 3 is a side elevation, illustrating the carrier in folded position and supported against a wall or similar structure.

Figure 4 is a side elevation of the carrier, illustrating one position of movement of the basket carriers, the framing structure and the wheel mountings, in solid lines, and an intermediate position of the parts being illustrated in dotted lines.

Figure 5 is a vertical sectional view of the carrier.

Figure 6 is an enlarged detail on the line 6—6 of Figure 5.

Figure 7 is a fragmentary enlarged detail of one of the front caster-wheel mountings,

Figure 8 is a similar view illustrating the rear wheel mounting.

There is illustrated a frame structure, generally indicated at 10, substantially rectangular in form, of strap metal and having side members 12 and end members 13 integrally connected, and longitudinally extended strap members 11, the latter being equally spaced from the side pieces 12 of the frame. The strap members 11 are welded or otherwise secured to the respective end portions 13 of the frame, and a transverse strap bar 14 is connected to respective side members 12, intermediate their lengths.

The frame 10 is pivotally mounted at respective sides to leg members 15, spaced outwardly of the frame, each leg having swivelly connected thereto a caster wheel 16.

The legs 15 are connected by means of a transversely extended bar 17, the bar being preferably welded to a flat face 18 of the leg. The bar 17 comprises forwardly extending arms 19 welded or otherwise secured to the lower extremities 20 of a handle member 21. The handle member 21 is substantially U-shaped in plan, the bight portion 22 forming the means whereby the carrier is propelled. The bight portion 22 is preferably covered by any suitable hand grip material, such as rubber, being indicated at 22. The side members 23 of the handle are integrally formed with the extension 20, as clearly shown in Figure 1, and preferably, these side members are slightly greater in width than the frame 10, each leg being inwardly offset, as at 24, to snugly rest against the respective legs 15, where they are welded. The extensions 20 are each welded to respective forward extensions 19, thereby giving a substantial rigid structure between the legs 15 and the side members 23.

A rear wheel mounting is indicated generally at 25, and as shown comprises a transverse bar 25, welded to a flat plate 27 of respective rear leg members 28. Each leg member 28 includes a right angular extension 29, adapted to lie flush against respective rear legs 30, to which they are welded. At the lower end of each leg 30 there is suitably secured a strap 31 offset as at 32, to define a fork for mounting of respective rear wheels 33, the wheels being rotatively supported upon an axle 34.

Each leg 28 is braced as at 35, one end thereof being pivotally connected to each rear leg 30, as at 36, the other end being pivotally connected as at 37 to the frame 10. The frame 10 is also pivotally connected as at 38, to respective front legs 15. The bar 26 of the rear leg mounting is positioned

so that the upper edge thereof is in alignment with the pivots 38, so that the frame 10 may be maintained in a horizontal position when the carrier is in erected position.

5 Each of the rear legs 30 are pivotally connected as at 39, to respective side portions 23 of the handle, and immediately therebeyond the leg is offset inwardly toward each other for pivotal mounting as at 39' of a basket carrier, generally indicated at 40.

10 The carrier 40 is rectangular in shape, defined by respective side members 41 and a forward end member 42, the rear end of the side members 41 being unconnected, for purposes which 15 will presently appear. Between the side members 41 suitable support bars 42 are provided, affording support of a basket or carrier when placed thereon. Each of the side members include a stop lug 44 positioned so as to engage 20 the upper extremities of the leg members 30, and when so engaged against the members 30 to maintain the basket support 40 in a horizontal position. In addition, a U-shaped strap member 45 is connected between the leg members 25 23 extending therebetween and adapted to engage the free ends of the side members 41, thus affording additional support to the basket carrier 40.

30 At a suitable distance below the pivot 39 a strap member 46 is secured between the side members 33, affording rigidity to the members 23, and further, cooperate with the free ends 41' of the side members 41 when the carrier support 40 is moved thereagainst, as is required 35 to move the various parts of the truck to its folded or collapsed position.

35 The front casters 16 may be of conventional type, embodying a yoke 47 having an integral spindle 48, adapted to be swivelly mounted in 40 a socket 49, the socket and spindle having a retaining ring 50 for maintaining the wheel detachably connected with the socket. The socket is preferably welded to the plate 16 on the inner side, as clearly shown in Figure 7.

45 By providing the offset portion 24 in the side members 23 of the handle, the front caster wheels will traverse a path inwardly of the tread of the rear wheels, and also, by this arrangement, when the truck is moved or collapsed, the rear 50 wheels will clear the front caster wheels by reason of their greater spring.

55 It will be assumed that the truck is in its collapsed or folded position as shown in Figure 3, wherein the extremities 20 are illustrated as resting upon the floor, and the handle portion 22' engaging a wall or other surface. It should be noted that the wheels are fully raised from the floor surface. In order to erect the parts in operative position, it is only necessary for a 60 user to grasp the handle 22 in one hand, while the other hand grasps the end rail 42 of the upper carrier. In such position, the extremities 41' of the carrier support 40 engages the cross bar 46. The caster wheels 16 now engage the 65 supporting floor surface, and upon release of the carrier 40 the rear legs 30 will be moved rearwardly, drawing the carrier frame 10 downwardly, as indicated in Figure 4, by dot and dash lines. After which movement of the rear legs 70 30 will be automatic, until the carrier 10 comes to rest on the frame member 26 of the rear legs. By reason of the pivotal connections of the basket carrier 40, the final horizontal position thereof may be obtained by reason of gravity, 75 until the free ends engage the bar 45.

When the truck is to be collapsed for storage purposes, the handle 22' is grasped, the carrier 40 swung upwardly and rearwardly toward the handle 22'. It will be noted, however, that before the carrier can pass inwardly between the 5 side members 23 of the handle, the outer ends 41' of the carrier will have engaged the cross bar member 46. Further movement of the carrier frame will obviously be prevented, and the side members 30 will pivot upon the pintles 39 10 and the pintles 36, causing the carrier 10 to swing upwardly between the side members 23 of the handle. This movement is continued until the full collapse position is attained, as shown in Figure 3, when the truck may be stored, as 15 shown.

It will be obvious that when this truck is in use, the upper carrier may be swung to a position extending upwardly at an angle with the extremities 41' engaging the cross bar 26, in 20 which position the lower carrier 10 is fully exposed so that goods may be readily placed in the basket or carrier supported thereon.

25 While I have shown and described my construction of carrier specifically, this is by way of illustration only, and I consider as my own all such modifications in structure as may clearly fall within the scope of the appended claims.

I claim:

1. In a folding wheeled carrier, a base frame 30 member, a pair of handle members pivotally connected to respective sides of the frame member adjacent one end thereof, said handle members extending diagonally upward, a wheel mount rigidly secured to the lower ends of the handle 35 members, a swivelled caster wheel carried by each wheel mount, a pair of rear wheels each including an upright leg member, fixed brace means between the leg members, a leg member being pivotally connected to respective handle 40 members and extending beyond the pivots, a brace link pivotally connected between each leg and the base frame member, a second frame member pivotally connected between the upper extremities of the leg members, said second 45 frame member having lugs positioned to engage respective leg members in one position of its swinging movement, a transverse bar connecting the handle members, positioned to engage the last named frame member when the lugs 50 engage said legs, and transversely extended means on the handles positioned to engage said last named frame member when the frame is moved beyond a vertical upright position whereby to swing said leg members forwardly and 55 said base frame member upwardly to a position substantially parallel to the handle members.

2. The structure of claim 1 in which the lower extremities of the handles extend beyond the 60 caster wheels and terminate in portions substantially vertical to the axis of the wheels.

3. In a folding wheeled carrier, a base frame member, a pair of handle members pivotally connected to respective sides of the frame member, 65 adjacent the forward end thereof, said handle members extending diagonally upward and having a hand grip portion, an angle plate fixed to each handle member extending vertically downward therefrom, a socket carried by each plate, a caster wheel swivelly mounted in each socket, a pair of rear wheels, each including an upwardly extended leg member, a brace member extended between and fixed to the leg members adapted to support one end of the base frame, a leg member being pivotally connected to respective 70 75 70 75 members.

handle members, the leg members being extended beyond the pivots, a brace link pivotally connected between each leg and the base frame member, a second frame member pivotally connected between the upper extremities of the leg members, said second named frame having lugs positioned to engage respective leg members when said frame is in horizontal position, a transverse bar connecting the handle members, positioned to engage the last named frame member when the lugs engage said legs, and transversely extended means on the handles positioned to engage said last named frame member when the frame is moved beyond a vertical upright position whereby to swing said leg members forwardly and said base frame member upwardly to a position substantially parallel to the handle members.

4. The structure of claim 3 in which the lower extremities of the handles extend beyond the caster wheels and terminate in downwardly turned angular portions.

5. In a folding wheel carrier, a substantially rectangular base frame member, a pair of handle members, said handle members having an inwardly offset portion and pivotally connected to respective sides of the frame adjacent an end thereof, said handles extending diagonally upward and having a hand grip portion, an angle plate fixed to each handle member adjacent the lower end thereof extending vertically downward therefrom, a socket carried by each plate, a caster

wheel swivelly mounted in each socket, a pair of rear wheels, each including an upwardly extended leg member, a brace member extended between and fixed to the leg members, positioned to support one end of the base frame when in horizontal position, a leg member being pivotally connected to respective handle members, the leg members being extended beyond the pivots, a brace link pivotally connected between each leg and the base frame member, a second rectangular frame member having longitudinal side elements unconnected at their rear ends, said side elements abutting respective upper ends of the leg members for pivotal connection thereto, a lug on each side element positioned to engage respective leg members when said frame is in horizontal position, a transverse bar connecting the handle members positioned to engage the last named frame member when the lugs engage said legs, and a transversely extended bar fixed to the handles positioned to engage said last named frame member when the frame is moved beyond a vertical upright position whereby to swing said leg members forwardly and said base frame member upwardly to a position substantially parallel to the handle members.

6. The structure of claim 5 in which the lower extremities of the handles extend beyond the caster wheels and terminate in a portion substantially vertical to the axis of the wheels.

SYLVAN N. GOLDMAN.
